UNITED STATES PATENT OFFICE.

JUDSON GOULD SPOFFORD, OF HOPEDALE, MASSACHUSETTS.

PROTRACTOR.

No. 926,615.

Specification of Letters Patent.

Patented June 29, 1909.

Application filed February 14, 1908. Serial No. 415,964.

To all whom it may concern:

Be it known that I, JUDSON GOULD SPOFFORD, a citizen of the United States, residing at Hopedale, in the county of Worcester, State of Massachusetts, have invented certain new and useful Improvements in Protractors; and I do hereby declare the following to be a full, clear, and exact description of the invention, such as will enable others skilled in the art to which it appertains to make and use the same.

This invention has relation to a new and useful improvement in protractors.

The object of my invention is to provide a draftsman's protractor adapted to be used in connection with an ordinary T-square and that will enable the user to adjust the blade to any angle required.

In the accompanying drawings I have shown in Figure 1 a face view of the protractor embodying my invention. Fig. 2 discloses a detached detail of the L-shaped member as used in my invention. Fig. 3 shows a face view of the bottom plate. Fig. 4 shows an enlarged central sectional view with portions broken away on the line 4—4 of Fig. 1. Fig. 5 shows an edge view of the blade, and Fig. 6, an end view of the protractor.

The improved device comprises two plates 2—6 having two of their edges $a'-b'$ at right angles to each other with the remainder of the plates segmental as at i with the center of the segmental portion spaced from the edges $a'-b'$ of the plates and with an aperture 5 in the plate 2 and a corresponding aperture 8 in the plate 6, the two apertures being in alinement, as indicated. The plate 2 is formed with a slot 4 curved concentric to the apertures 5—8. The plates 2—6 are united at their right angled edges by an L shaped member 1, the L shaped member thus spacing the plates apart and being secured between them by rivets or other suitable fastening means. By this means the segmental edges of the plates are spaced apart while the right angled edges of the plates are closed by the L shaped member B.

Extending through the apertures 5—8 is a pin 9 having an annular central flange 14, the ends of the pin extending through the apertures and the flange extending between the plates 2—6, the flange thus forming shoulders upon which the plates bear, and likewise providing a central bearing between the

plates larger than the apertures. Swinging upon this enlarged central portion 14 is a blade 11 having an aperture 10 corresponding to and engaging the enlarged or flanged portion 14 of the pin 9, the blade thus having a relatively large bearing between the plates. The outer portion of the blade is thicker than the portion between the plates as at 12 whereby shoulders are formed which engage the outer or segmental edges of the plates, as at 13—14 in Fig. 5. The portion 11 of the blade is provided with a threaded aperture opposite the slot 4 and engaging this aperture is a threaded clamp screw 15 having a shoulder 17 and a milled head 16 whereby the screw may be operated and clamp the three parts 2—6—11 firmly together when required. The shoulders 13—14 thus provide for a bearing against the segmental outer edges of the plates 2—6 and the upper and lower surfaces of the blade 12 come flush with the upper and lower surfaces of the plates, as shown in Figs. 4 and 6.

When the implement is in use one of the sides $a'-b'$ will be disposed upon a suitable rule or straight edge, preferably the blade A of a T square, as shown.

Formed upon the plate 2 between the slot 4 and the segmental edge of the blade are graduations representing degrees of a circle from zero to ninety while upon the blade 12 is a vernier x , to assist in setting the blade to the required angle.

The plate 6 is formed with numerous radial lines emanating from the center of the aperture 8 and the face of the plate is again divided by a plurality of segmental lines which divide the radial lines into sections, the spaces between the radial lines and the segmental lines having the values of sines, cosines and tangents for every five degrees, the radial lines coöperating with the degree lines on the face of the opposite plate. By this simple means it is obvious that the blade 11 may be set at any required angle.

The improved implement will be employed, as above stated, in connection with a straight edge, preferably with the blade of a T square as shown, and by its use any required angle may be transferred to the paper on a drawing board by simply loosening the screw 16 and moving the blade to the required extent.

The plate 6 and the lower face of the blade 12 coming flush with each other lie flat upon

the paper, and thus facilitate the operation, and remove very largely the element of uncertainty to the action of the device.

The device is simple in construction, can be inexpensively manufactured, and will be found very useful for draftsmen and engineers in laying out work, or in transferring to paper the routes made by the surveyors, and for other like purposes.

10 The plates 2—6 and the L shaped member 1 will preferably be of metal and may be plated or otherwise ornamented and protected, while the blade 11—12 may be of wood, metal, or other material as may be 15 preferred.

What is claimed, is:—

1. A device of the class described comprising a head portion consisting of a member formed of two rigid arms extending at right angles to each other, two plates connected at the opposite sides of said bars and provided with graduations, and with transversely alined bearing apertures therethrough in advance of said member, the free edges of the 25 plates being segments of circles of which the centers of the apertures form the center, one of the plates having a slot concentric to the segmental edge of the blade, a pin extending in said bearings, a blade with the outer portion equal in thickness to the combined thickness of the plates and said member and with a reduced portion extending between

said plates and swinging upon said pin, and clamping means operating through said segmental slot.

2. A device of the class described comprising a head portion consisting of a member formed of two rigid arms extending at right angles to each other, two plates connected at the opposite sides of said bars and provided with graduations, and with transversely alined bearing apertures therethrough in advance of said member, the free edges of the plates being segments of a circle of which the apertures form the center, one of the plates 45 having a slot concentric to the segmental edge of the plate, a pin extending in said bearings, a blade with the outer portion equal in thickness to the combined thickness of the plates and said member and with the 50 reduced portion extending between said plates and swinging upon said pin, the reduced portions forming concaved shoulders bearing closely upon the curved outer edges of the plates, a vernier upon said blade co-acting with the graduations on the plate, and clamping means operating through said segmental slot.

In testimony whereof, I affix my signature, in presence of two witnesses.

JUDSON GOULD SPOFFORD.
